UNITED STATES PATENT OFFICE

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS

SHOE RACK

Application filed June 6, 1929. Serial No. 368,904.

This invention relates to shoe racks, having reference more particularly to racks for domestic use adapted to conveniently support shoes when not in use. My improved shoe rack has been designed more especially for closet use, being well adapted to be mounted on the inner side of a closet door, whereby, when the latter is closed, the rack and its contents are out of sight. It will be manifest, however, that, so far as the structural features of the rack itself are concerned, it may be mounted on any suitable or convenient support.

The principal object of the invention has been to provide a very simple, efficient, and inexpensive shoe rack for domestic use capable, as above stated, of being mounted on the inner side of a closet door. Another object has been to provide a rack which will support the shoes in a manner permitting free circulation of air around all parts of the shoe and free drainage of any moisture that may drip from a wet shoe when mounted on the rack. Still another object has been to provide a shoe holder readily adjustable to accommodate varying sizes of shoes; and a still further object has been to provide a shoe holder that will securely hold the shoe by the instep portion of the upper without any danger of cutting, scratching or otherwise marring the leather.

Still other objects and inherent advantages of the invention will be apparent to persons skilled in the art as the same becomes better understood by reference to the following detailed description, taken in connection with the accompanying drawings, in which I have illustrated a simple and practical mechanical embodiment of the invention and the preferred mounting and location thereof, and wherein—

Fig. 1 is a front elevation of the device, indicating by dotted lines, a shoe mounted in one of the shoe holders.

Fig. 2 is a top plan view, also showing in cross section a shoe mounted in one of the shoe holders.

Fig. 3 is an end elevation, viewed from the right of Fig. 1.

Fig. 4 is a top plan view of the right hand

arm of one of the shoe holders, as seen in Fig. 1.

Fig. 5 is an enlarged horizontal section through the pivot and clamp of one of the shoe holders.

Fig. 6 is a perspective view of the lower portion of a closet and closet door, showing my improved shoe holder mounted on the inner side of the latter.

Referring to the drawings, 10 designates a flat horizontal bar, preferably of metal, apertured at its ends for attachment to a suitable supporting surface. At spaced intervals on the bar 10 are mounted a plurality of shoe holders, and since these holders are all alike, a description of one will suffice for all. In the form illustrated, the holder comprises a pair of upwardly divergent arms 11 and 12, preferably composed of flat metal strips. The lower portions of these arms are overlapped, as shown, and pivotally attached to the bar 10 by a single pivot stud 13, whereby the arms can be adjusted angularly relative to each other to vary the width of the space between their upper ends. At their upper ends the arms 11 and 12 are formed with blunt tip portions which are designed to engage with the instep portion of the upper just above the sole of the shoe, as clearly indicated in Figs. 1 and 2. These blunt shoe engaging tip portions may be variously formed, but in the structure illustrated I have shown the upper portions of the arms 11 and 12 formed of reduced width and bent laterally as at 14 and thence upwardly as shown at 15, the upwardly bent portion 15 being extended beyond the portion 14 in the direction of the inner edge of the arm, and said extension being then bent backwardly by a suitable swaging tool to produce a shoe engaging tip 16, the outer surface of which is rounded both lengthwise and crosswise so as to obviate any danger of cutting, scratching, or otherwise marring the surface finish of the shoe upper.

As will be readily seen from Fig. 2, the inwardly offset tip extensions last described are the same on the two arms 11 and 12, but inversely arranged.

The two arms of the holder, being mounted in scissors fashion on a common pivot stud,

are, of course, capable of being adjusted angularly both with reference to each other and with reference to the main supporting bar 10, so as to accommodate wider or narrower shoes; and in Figs. 1 and 5 I illustrate a simple means for securing the holder arms in any adjusted position. It will be observed that both arms are pivoted adjacent to one longitudinal edge, and opposite the pivot point the arms are provided with registering arcuate slots 17, through which is passed a binding screw 18 screwing into a tapped hole in the bar 10, said binding screw, through a washer 19 serving, when turned up, to securely clamp the arms in adjusted position, in which position, each arm has a pair of spaced supports 13 and 18 holding the arm very securely against angular displacement. To adjust the width of the holder it is necessary only to slacken the clamp screw 18, set the arms to the desired position, and then retighten the clamp screw.

In Fig. 6 I have illustrated the principal intended manner of use of the shoe rack. The bar 10 is attached by screws 20 to the vertical frame members 21 of a closet door, opposite one of the inset panels 22 of the latter. The shoe is mounted, sole inwardly, on the holder by simply sliding the instep portion of the upper downwardly into engagement with the tips 16 of the holder arms, in a manner clearly indicated in Figs. 1 and 2. The shoe may be mounted either tip upwardly or heel upwardly, and in either position substantially the entire outer surface of the shoe is exposed to the drying influence of the air circulating therearound. And since the lower edge of the ordinary closet door is more or less spaced from the floor, when the door is closed air flowing through the crack between the door and the floor circulates upwardly around the shoes and exerts a drying effect, if the shoes are wet when put away. When the shoe is supported upright and held downwardly, as indicated in Fig. 4, the holder readily permits any excessive moisture in the shoe to drain out through the heel of the latter.

I have herein shown and described one practical and efficient embodiment of the invention, but, manifestly, the structural details may be variously modified within the principle of the invention without any departure from the principle or sacrificing any of the advantages thereof. Hence, I do not limit the invention to the specific form shown, but reserve such variations and modifications as fall within the spirit and purview of the appended claims.

I claim:

1. A shoe rack, comprising a horizontal bar, and a plurality of generally V-shaped shoe holders mounted thereon in spaced relation, said holders each comprising a pair of upwardly divergent arms pivoted coaxially to said bar and at their upper ends formed

with blunt tip portions adapted to supportingly engage the instep portion of a shoe upper.

2. A shoe rack, comprising a horizontal bar, and a plurality of generally V-shaped shoe holders mounted thereon in spaced relation, said holders each comprising a pair of upwardly divergent flat arms the lower portions of which overlap each other and are secured to said bar by a single pivot stud, said arms at their upper ends being formed with laterally offset blunt fingers adapted to supportingly engage the instep portion of a shoe upper.

3. A shoe rack, comprising a horizontal bar, and a plurality of shoe holders mounted thereon in spaced relation, each of said holders comprising a pair of upwardly divergent angularly adjustable arms pivoted at their lower portions to said bar and formed at their upper ends with blunt tip portions adapted to engage the opposite sides of a shoe upper, and means for securing said arms in any angularly adjusted position.

4. A shoe rack, comprising a horizontal bar, and a plurality of shoe holders mounted thereon in spaced relation, each of said holders comprising a pair of upwardly divergent angularly adjustable flat arms overlapping each other at their lower portions and secured to said bar by a common pivot stud, said arms being formed at their upper ends with blunt fingers adapted to engage the opposite sides of a shoe upper, and means for securing said arms in any angularly adjusted position.

5. A shoe rack, comprising a horizontal bar, and a plurality of shoe holders mounted thereon in spaced relation, each of said holders comprising a pair of upwardly divergent angularly adjustable flat arms overlapping each other at their lower portions and secured to said bar by a common pivot stud, said arms being formed at their upper ends with laterally offset blunt fingers adapted to engage the opposite sides of a shoe upper, and having registering arcuate slots located opposite said pivot stud, and a clamp screw extending through said slots into said bar.

JAMES H. BOYE.
